CLAIM

The ornamental design for a handle hooking device, as shown and described.

DESCRIPTION

FIG. 1 is a side view of the handle hooking device showing my new design;

FIG. 2 is the other side view thereof;

FIG. 3 is a front view thereof.

FIG. 4 is a rear view thereof,

FIG. 5 is a top view thereof;

FIG. 7 is an illustrative perspective view thereof.

The broken line showing of a cleaning device handle and a trash can is included for the purpose of illustrating environment and forms no part of the claimed design.
